I. MILLER.

AMUSEMENT GRAVITY SUSPENSION RAILWAY

Filed Nov. 22, 1926

Inventor,
ISIDOR MILLER,
By Julian J. Wittal
Attorney.

UNITED STATES PATENT OFFICE.

ISIDOR MILLER, OF UNION CITY, NEW JERSEY.

AMUSEMENT GRAVITY SUSPENSION RAILWAY.

Application filed November 22, 1926. Serial No. 149,951.

This invention relates to amusement devices adapted for use in parks and seashore and other resorts where crowds of people congregate, an object being to provide such a device whose operation is substantially automatic and quite inexpensive.

The invention has for its further objects to provide certain other novel features, all of which will be more clearly defined in the following detailed description.

Some of the said features comprise spaced towers or masts which may be positioned in a path returning to its original start and on which is a cable constituting a runway for a roller support, seat, car, or cage. These towers are preferably graduated in height, the one at the beginning of the runway being the tallest or highest and each succeeding tower in the circle being lower in stepped relation; the last one, the one at the end of the runway being lowest of all.

The towers also may be of equal heights, in which case they carry supports for the runway placed of gradually diminishing heights on the towers. The towers may be of any desired number and the path of the runway may take any desired shape, like circle, rectangular, polygonal, or other curvature according to the space available to be covered by my device.

I also may employ several supports on each tower and provide a multiple path or runway for my cars, covering the same curve several times at gradually diminishing heights.

To move the car from the loading point, at the lowest tower, to the starting point of the cable runway, I may provide a motor driven elevator constituted by an endless chain or belt provided with projections to engage a part of the cage or car hanger and draw the said car up an inclined portion of the cable to the top of the highest tower after which it is released and starts, by the action of gravity, another trip along the cable down to the lowest or loading point.

By the construction described it will be seen the only power required is for the intermittent operation of the elevator.

I clearly illustrate my invention in the accompanying drawing, which forms a part of this specification, and in which drawing similar reference characters are employed to designate corresponding parts throughout the several views, in which:—

Fig. 1, is a diagrammatic perspective view

showing the complete arrangements of the amusement device with the passenger carrying car or cage at the loading point.

Fig. 2, is a fragmentary elevation showing a cable supporting arm extending outwardly from the top of a tower and showing the car hanger mounted on the cable.

Fig. 3, is a fragmentary side view showing some of the inclined cable portion, the cage hanger with its roller and a length of the elevator with one of its projections or lugs engaging a loop of the cage hanger to pull it up to the top of the highest tower of the amusement device.

Fig. 4, is a diagrammatic plan view of the arrangement of my device with a particularly shaped runway.

Referring to the drawings, I preferably provide a series of towers 10, 11, 12, 13, 14 and 15, graduating in height from the first to the last, the tower 10 being the tallest or highest.

Each of these towers has an outwardly directed arm 16, provided at its remote end with a support 17, for an endless cable 18 constituting a runway for a car or cage 19, suspended by a hanger 20, therefrom, which may be formed with a shank 21, a loop 22, a cross bar 23, and a guard finger 24, being a downward extension of the inner side of loop 22. A roller 25, is journalled on the bar 23, and has a deep groove 26, to hold it to the cable at high speed, but if it should jump the cable the shank 21 on the one side and guard finger 24 on the other will prevent the car from getting off the cable and dropping to the ground, as will be understood.

When the car is loaded, it may be pushed by attendants a few feet to an elevator 27, constituted by an endless belt or chain 28, carried on pulleys or gears 29, and 30, suitably mounted on the towers 15 and 10 respectively, gear 29 being driven by a motor 31, controlled by a switch 32.

The endless chain elevator is provided with spaced projections or fingers 33, one of which, in the operation of the device, will engage the loop 22, of the car hanger and carry it to the top of the tower 10, when it will be released by the loop passing away from the engaging finger as it is carried around the gear 30, while the cable 18 starts on its downward grade with the car rolling downwardly thereon.

To insure positive engagement of a finger

33, of the elevator with the loop 22 I may back up the lower reach thereof with pressure rolls 34.

The car 19, when it is coming from the tower 14, on the last horizontal cable section 18^a has lost considerable momentum and the device will be so designed that the car should stop at the desired place but enough momentum may still remain to render it rather difficult to bring the car to a full stop at the proper place to unload the passengers. I have overcome this difficulty by providing a series of rollers 35, mounted at the unloading platform and against which a spring pressed brake block 36, presses so that the friction set up by the rollers will bring the car to a stop at the proper point at the platform.

The car may also be caused to stop at the right position by making the lowest end of the runway at tower 15, somewhat raised, as indicated by the dotted lines at 15^a, so that the car will naturally roll back to the loading position.

To facilitate the rounding of the corners where the towers, or masts are located, I may conveniently arrange two or more arms on the respective towers projecting therefrom in radial directions so as to give easier curvature to the cable. I may also insert curved pieces of rods, rails etc. at the corners or may, naturally, build the whole runway of rods, rails or the like instead of the cable.

In Fig. 4 I illustrate in a diagrammatic plan view a specific arrangement of my towers or mast 10', 11', 12', 13', 14', 15', 16', 17', 18', and 19', the first one being the highest and the last one the lowest, carrying the runway 18^a in a steadily declining manner and having the elevator 27^a inserted between the last and the first towers, as has been described hereinabove.

With this diagrammatic figure I want to illustrate the great adaptability of my amusement device to the space available, it being adapted to cover quite a large space in any desired line or curvature and still leaving the ground entirely free for other devices arranged underneath my runway, with the exception of the small ground spaces needed for the erection of my towers.

Finally I want to remark that based on the principles disclosed herein, my amusement device may be built with two towers only, the runway being between the two and the car running to and fro between them for which purpose the ends of the runway and the car on them are alternately raised and lowered. It is also obvious that aside of the

gravity drive described hereinbefore I may employ any of the usual and well known power or hand drives to propel my car along its runway and through these methods or through the general design of the device I may give my car any desired speed.

Instead of a power driven elevator I may employ any of the well known hand devices, based on lever and gear systems to lift my car at the end of its travel.

What I claim as new is:

1. An amusement device comprising in combination with a car having a hanger and a roller thereon, a series of supports arranged in a substantially closed continuous path a cable thereon forming a runway for said car from which it is suspended, said supports being of progressively decreasing heights from the beginning to the end of the runway and means for raising said car from the end to the beginning of said runway, said means comprising a motor driving endless chain having projecting fingers to engage the hanger of said car, and means to stop the car at the end of the runway including friction rollers to contact the bottom of the car.

2. An amusement device comprising in combination with a car having a hanger and a roller thereon, a series of supports arranged in a substantially closed continuous path a cable thereon forming a runway for said car from which it is suspended, said supports being of progressively decreasing heights from the beginning to the end of the runway and means for raising said car from the end to the beginning of said runway, said means comprising a motor driving endless chain having projecting fingers to engage the hanger of said car, said hanger having a loop, a cross bar on which the roller is journaled, and a guard finger arranged inside of 100 said cable.

3. In an amusement device in combination, a series of towers, a cable carried thereon to form a runway, a car having a roller to engage said runway said towers being of varying heights, the tallest being at the beginning of the runway, the shortest at the end of said runway, means for transferring said car from the shortest to the tallest tower and means for stopping the car at the end of the runway, including friction rollers to contact the bottom of the car at the end of the runway.

Signed at New York, in the county of New York and State of New York, this 8th day of November, A. D. 1926.

ISIDOR MILLER.
